UNITED STATES PATENT OFFICE.

PAUL WORTH, OF AKRON, OHIO, ASSIGNOR TO THE INDIA TIRE AND RUBBER COMPANY, OF MOGADORE, OHIO, A CORPORATION OF OHIO.

DESIGN FOR A RESILIENT TIRE.

Application filed January 21, 1924. Serial No. 8,362. Term of patent 14 years.

To all whom it may concern:

Be it known that I, PAUL WORTH, a citizen of the United States, residing at Akron, in the county of Summit and State of Ohio, have invented a new, original, and ornamental Design for Resilient Tires, of which the following is a specification, reference being had to the accompanying drawings, forming a part thereof.

In the drawings:

Figure 1 is a plan view looking upon a section of a tire showing my new design;

Figure 2 is a longitudinal section on the line 2-2 of Figure 1.

I claim:

The ornamental design for a resilient tire, as shown.

PAUL WORTH.
